Patented Apr. 7, 1925.

UNITED STATES PATENT OFFICE.

JOHN G. BLESSING, OF CHICAGO, ILLINOIS, ASSIGNOR TO AUTOMATIC ELECTRIC COMPANY, OF CHICAGO, ILLINOIS, A CORPORATION OF ILLINOIS.

AUTOMATIC CALLING DEVICE.

Application filed January 21, 1921. Serial No. 438,998.

To all whom it may concern:

Be it known that I, JOHN G. BLESSING, a citizen of the United States of America, and a resident of Chicago, Cook County, 5 and State of Illinois, have invented certain new and useful Improvements in Automatic Calling Devices, of which the following is a specification.

My invention relates in general to a calling device or impulse transmitter for use 10 in an automatic telephone system of the standard two wire type in which the automatic switches are operated by impulses of current resultant upon the opening and 15 closing of the series line circuit at the telephone.

Among the features of my invention are, 20 an improved governor for controlling the speed of the impulses, said governor having means for disengaging itself from the 25 remainder of the mechanism allowing itself to spin after the desired impulses are sent in and stopping by the friction produced by itself, thereby removing any strain on the 30 governor which would be produced should the governor be stopped by any mechanical projection placed in the area traversed by it.

Another feature of my invention is the 35 provision of means for increasing the period of time between series of impulses, the long space between the first number hole and the stop increasing the period between digits giving the time effect of a larger number.

It is a well known fact that in the Strowger selector a certain period of time after 40 making vertical movement is necessary to allow the switch to seek an idle trunk and therefore in ordinary dialing the period allowed for the movement is very short when 45 a small number is dialed, for it will be seen that an impulse might be lost due to the fact that the selector might not have completed its rotary motion when the next impulse comes in.

Other detailed features of improvement which tend to simplify the construction and improve the operation and general efficiency of the device will be hereinafter pointed out.

Fig. 1 of the drawings shows a front view 50 of the calling device with a part of the spring cover cutaway to show the spring.

Fig. 2 is a rear view of the calling device showing the governor and cam inter- 55 rupter.

Fig. 3 is an edgewise view of the calling device, showing the shunt and interrupter springs and the cam in normal position.

Fig. 4 shows a front view with the finger-hole dial and the number dial removed, 60 showing the gears and other mechanical parts.

Fig. 5 is a rear view of the finger hole plate with a part of the unit gear and ratchet broken away to show more clearly the 65 operating element.

Fig. 6 is a diagrammatic sketch of the cam and its driving gear in normal position.

Fig. 7 is the same as Fig. 6, but showing 70 the elements in their operated position.

Fig. 8 is an edgewise view of the governor showing the unit gear and ratchet which is loosely attached thereto.

Fig. 9 is another view of the governor 75 from the side to which the pinion is attached, showing the combined spring and pawl.

I will now describe the various parts of 80 the calling device more in detail and explain the operation of the same, reference being made to the various figures of drawings.

My improved calling device consists of 85 a mounting plate 11 (see Fig. 3), one side having a raised shoulder 21 (Fig. 2) eccentric with the outer edge of the mounting plate and on which are formed two lugs 22 and 23 which serve as means for attaching the device to the base of the telephone 90 and also providing wide surfaces for extending the cam shaft 24 through (Fig. 3) and for mounting the interrupter and shunt springs 27, 25 and 26. Another part of the shoulder projects which is concentric with 95 the outer edge of the plate and has a depression therein, in which the governor rotates (see Fig. 2).

The opposite side of plate 11 has a shoulder 30 around its outer surface to form a 100 shallow cup for the dial 17.

Another depression deeper and eccentric with the outer edge of the plate 11 has within its area, a raised portion 31. On part 31 is mounted a plate 32 having on one side a 105 shaft 33 (see Fig. 2) extending through the rear of the plate 11 and on the other side a stud 34 (Fig. 4) internally threaded to receive the screw 16.

The screw 16 has a small ear projecting to 110

engage one end of the power spring 18 and also acts to hold the finger hole dial 38 to the mounting plate 11. Raised part 31 is also used as a mounting plate for the spring 40.

In another part of the depression of the plate 11 is a shaft on which is loosely mounted the gear and pinion unit 41 and 42. To gear 43 is also mounted in this recessed portion firmly attached the shaft 24 (Fig. 3) which as will be seen projects through the plate 11.

The finger hole dial 38 has on its front a cup 19 for holding the spring 18 and also 15 has a notch cut in one side of same for permanently fastening one end of the spring. On the other side of the finger hole dial is a projecting sleeve 44 (Fig. 5) which has 20 loosely mounted thereon the unit ratchet and gear 36 and 35.

A pawl 45 is secured to the underside of the finger plate 38 and is held in engagement with the ratchet 36 by a spring 46 so that as the dial rotates in one direction the 25 pawl 45 slides over the ratchet 36 and the ratchet and gear remain stationary, but as the dial returns it carries the ratchet and gear with it.

When the finger hole plate is mounted in 30 place on the stud 34 on the plate 11 the gear teeth 35 operate the gear 55 of the governor through the medium of gears 42 and 41 (Figs. 8 and 9) which governor is mounted on the shaft 33 (Fig. 2). On the under- 35 side of the finger hole dial and near the edge of same is a projecting pin 48 which normally rests against the projecting screw 13 on the finger stop 14 under the tension of the power spring 18.

The governor (see Figs. 8 and 9) is loosely mounted on the hollow shaft of the unit gear and ratchet 55, the spring pawl 53 engaging with the teeth of the ratchet 52 so that when the gears operate the governor is 45 rotated also but when the gears come to a stop the governor continues to rotate free from the other operating parts.

As before pointed out the dial is so arranged that when operated to send the digit 50 1 for instance, the cam is rotated through 2 complete revolutions and unless some means were provided to prevent it, it will be seen that the springs 27 would be twice opened and 2 impulses transmitted. However, in 55 Figures 6 and 7 I have shown in detail the mechanism for rendering the last revolution of the cam ineffective to so interrupt springs 27, and for making the cam shaft effective to operate the cam springs 25 and 26. As 60 the dial 38 returns to normal when operated in accordance with any digit the roller 49 rides up on the lug 50 for a distance equal to that required to revolve the cam once. The cam 60 and the gear 43 being slidable 65 endwise will thus be forced to the left as

shown in Fig. 6 and while the cam is still revolving it will be out of the path originally traversed, and will therefore not interrupt the spring 27. This endwise movement of the shaft 24 causes the spring 25 to be 70 moved out of engagement with the spring 26. Also the movement of the lug 50 causes a projection thereon to be brought into the path of the pins 51 on the gear 41 thus effectually stopping all further movement of 75 the gears.

Thus it will be seen that even though the dial 38 moves through the space equal to an added impulse each time it is operated, yet this movement is used only to operate the 80 shunt springs.

What I claim as my invention is:

1. In a calling device, a combination of shunt and interrupter springs, a shaft having a cam fixed thereto, and mechanism associated therewith for operating said shaft during one period to directly engage and operate said shunt springs and during another period to alternately open and close said interrupter springs through the medium of said cam.

2. In a calling device, a cam, interrupter springs, mechanism associated therewith having means for rotating said cam twice, and means automatically effective during one of said rotations to move said cam out of range of said springs to permit said cam to open said springs only once.

3. In a calling device, a rotatable cam, impulse springs normally operated by said cam at each rotation thereof, and mechanism for laterally moving said cam to cause one operation to be omitted whenever said cam is rotated a plurality of times.

4. In a calling device, a combination of 105 springs, a shaft having a cam fixed thereto, said shaft laterally operated at one time for operating one pair of said springs and rotated at another time for operating another pair of said springs through the medium of 110 said cam.

5. In a calling device, interrupter springs, a cam, and mechanism associated with said device for rotating said cam to interrupt said springs, said mechanism co-operating 115 with said cam to prevent the same from operating said springs during a certain revolution.

6. In a calling device, an impulse transmitting cam, and means for operating said cam one revolution in one plane with respect to the calling device and for operating it one or a plurality of revolutions in another plane with respect to the calling device.

7. In a calling device, a cam and a gear assembly, a pair of interrupter springs associated therewith, an extending arm over said gear, and a dial having means for moving said arm to permit said cam to engage 130

with said interrupter springs during one period of operation, and for again moving said arm to allow said cam to assume another position during another period.

5 8. In a calling device, a cam, interrupter springs controlled thereby, a rotatable finger hole dial therefor, said cam movable during the rotation of the dial to permit it to operate said springs, and laterally movable during the continued rotation of the dial to prevent its operation of the springs.

10 9. In a calling device, interrupter springs and shunt springs, a shaft having a cam fixed thereto and moved by the device in one plane to permit said cam to operate said interrupter springs and moved in another plane to operate said shunt springs.

15 10. In a calling device, interrupter springs, a cam, a finger hole dial for rotating said cam at one time to interrupt said springs, and for rotating the cam at another time in another plane without interrupting said springs.

20 11. In a calling device, a gear train, impulse sending mechanism controlled thereby, a projection on one of the gears of said train, a finger dial for operating said gear train, a stop, and means on said dial for moving said stop into the plane of rotation 25 of said projection to stop said gear train.

25 12. In a calling device, springs, an endwise movable shaft carrying a cam for controlling said springs, a movable arm for operating said shaft endwise, a gear train for 30 operating said shaft, projections on one of the gears of said train and means for moving said arm into the path of said projections to stop said gear train when the arm is operated to move the shaft.

35 40 13. In a calling device, shunt and interrupter springs, a shaft having a cam mounted thereon, said shaft operating to open said shunt springs during one period and operating said interrupter springs during another period through the medium of said cam.

45 45 14. In a calling device, a pair of spring combinations, a shaft having a cam mounted thereon, a finger hole dial therefor which 50 operates said shaft in one manner to control only one spring combination and which operates said shaft in another manner to control only the other spring combination.

55 55 15. In a calling device, a cam, means for rotating said cam any desired number of times, an impulse spring normally operated by said cam at each rotation thereof, and means for causing said cam to miss the spring once and only once out of any plurality of consecutive rotations.

60 16. In a calling device, a cam, means for

producing consecutive rotations of said cam in groups, each group comprising any desired number of rotations, an impulse spring normally operated by said cam at each rotation thereof, and means for moving the cam to cause the operation of said spring to be omitted in the case of one rotation of each group.

65 17. In a calling device, a cam, means for producing consecutive rotations of said cam in groups, each group comprising any desired number of rotations, an impulse spring normally operated by said cam at each rotation thereof, and means for moving the cam to cause the operation of said spring to be omitted in the case of the last rotation of each group.

70 18. In a calling device, a cam, means for producing consecutive rotations of said cam in groups, each group comprising any desired number of rotations, impulse springs normally operated by said cam at each rotation thereof, and means operated independent of said springs for causing the cam to miss the spring on the last rotation of each group.

75 19. In a calling device, a cam, means for producing consecutive rotations of said cam in groups, each group comprising any desired number of rotations, an impulse spring normally operated by said cam at each rotation thereof, and means for changing the plane of rotation of said cam just prior to the last rotation of each group in order to prevent the operation of the said spring.

80 20. In a calling device, impulse and shunt springs, a shaft for operating said shunt springs and carrying a cam for operating said impulse springs, a finger hole dial having a projecting element, a movable arm, said element normally holding said shaft and cam out of alignment with said impulse springs through the medium of said arm, said shaft and arm responsive to tension in one of said shunt springs when the dial is moved upon initiation of the setting operation to bring said cam into alignment with said impulse springs.

85 110 21. In a calling device, springs, a shaft carrying an impulse cam, said shaft movable endwise, a rotatable finger hole dial, a projecting member on said dial, an arm engaging said shaft, said member moving said shaft endwise through the medium of said arm while the cam is rotating to operate said springs.

90 95 115 Signed by me at Chicago, Illinois, this 13th day of January, 1921.

JOHN G. BLESSING.
